UNITED STATES PATENT OFFICE.

JOHN C. FITCH, OF THREE RIVERS, MICHIGAN.

GRAVE VAULT.

Application filed October 29, 1921. Serial No. 511,488.

To all whom it may concern:

Be it known that I, JOHN C. FITCH, a citizen of the United States, residing at Three Rivers, county of St. Joseph, State of Michigan, have invented certain new and useful Improvements in Grave Vaults, of which the following is a specification.

This invention relates to improvements in grave vaults.

10 The object of the invention is to provide an effective concrete structure which can be very readily handled and placed and which may also be very readily sealed up.

15 Objects relating to details and economies of construction and operation will definitely appear from the detailed description to follow.

20 I accomplish the objects of my invention by the devices and means described in the following specification. The invention is clearly defined and pointed out in the claims.

25 A structure which is a preferred embodiment of my invention is fully illustrated in the accompanying drawing, forming a part of this application, in which:

Fig. I is a perspective view of my improved grave vault.

30 Fig. II is a longitudinal detail sectional view through the same, showing a coffin or burial casket in position.

Fig. III is a detail plan view in reduced dimensions of the base portion.

35 Fig. IV is a detail sectional view through a corner of the base and cover portion, showing the same sealed.

In the drawing similar numerals of reference refer to similar parts throughout the several views.

40 Considering the numbered parts of the drawing, 1 is a base of reinforced concrete hollowed out on the under side at 2 and extended upwardly into a raised platform 3 at the central portion.

45 Outwardly from flat platform extend flanges 4 with upwardly projecting outer retaining ribs 5 around the same. Four loops of metal 6 are carried on the upper face of the platform to serve as supports for the burial casket raised thereon and also to afford the means for attaching the lowering cords or devices.

The cover 8 is dome-shaped and adapted to fit the edges of the raised platform 3 and rests upon the flanges 4, the same being of such dimension that a space is left between 55 the rib 5 and the bottom thereof.

Four loops 9 are passed into the top of the cover 8 for handling the same by the usual lowering devices.

When the structure is placed as it appears 60 in Fig. II there is very complete and effective drainage from the interior.

When it is desired to seal the vault, a little concrete or mortar can be placed within the rib 5, as at 10,—see Fig. III, when a 65 completely sealed vault is secured. The mortar can be very readily placed in this groove from the top, avoiding any special enlargement of the grave.

I have shown the structure in the form 70 preferred by me, but wish to state that the details can be considerably varied without departing from my invention, and I desire to claim the same broadly and specifically as pointed out in the appended claims. 75

Having thus described my invention, what I claim as new and desire to secure by Letters Patent is:—

1. In a grave vault, the combination of a concrete base with a raised central platform 80 portion, flanged edge and upturned rib, provided with supporting loops cast in the base which serve as handles, a dome-shaped top portion conformed to fit around the platform of said base, and loop handles on the 85 said dome, as described.

2. In a grave vault, the combination of a concrete base with a raised central platform portion and flanged edge, provided with supporting loops cast in the base which 90 serve as handles, a dome-shaped top portion conformed to fit around the platform of said base, and loop handles on the said dome, as described.

In witness whereof, I have hereunto set 95 my hand and seal in the presence of two witnesses.

JOHN C. FITCH. [L. S.]

Witnesses:

EUGENE A. SCHALL,
GEORGE R. SKEER.
